UNITED STATES PATENT OFFICE.

GERRY JONES, OF BINGHAMTON, NEW YORK, ASSIGNOR TO EDWARD F. JONES, OF BINGHAMTON, NEW YORK.

CORNER-BRACKET FOR PITLESS WAGON-SCALES.

971,757.

Specification of Letters Patent.

Patented Oct. 4, 1910.

Application filed October 12, 1908. Serial No. 457,304.

To all whom it may concern:

Be it known that I, GERRY JONES, of Binghamton, in the State of New York, have invented new and useful Improvements in 5 Corner-Brackets for Pitless Wagon-Scales, of which the following, taken in connection with the accompanying drawings, is a full, clear, and exact description.

This invention relates to certain improvements in corner brackets for pitless wagon scales, in which the primary object is to 10 secure the meeting ends of the side and end bars of the rectangular frame together by corner brackets which also serve as supports 15 for the main supporting frame adapted to rest upon the surface of the ground and at the same time receive and support the platform levers which are connected to the weighing beam. In other words I have 20 sought to construct the frame of a pitless wagon scales with as few parts as possible so that it may possess the qualities of lightness, strength and durability.

Other object and uses will appear in the 25 following description.

In the drawings—Figure 1 is a perspective view of the main supporting frame showing the corner brackets and levers together with the frame for the weighing beam and counter levers. Fig. 2 is an enlarged perspective view of a portion of one corner of the frame showing one of the corner brackets and manner of attaching the platform levers thereto. Fig. 3 is a sectional view through 30 one corner of the frame and one of the corner brackets showing the clevis supporting braces in section together with the clevis beam and one of the platform supporting levers. Fig. 4 is a diagonal sectional view 35 across one corner of the frame, through the corner bracket and clevis supporting brace showing also the clevis and adjacent end of the platform supporting lever in section.

The main supporting frame preferably 40 consists of opposite side bars —1— and opposite end bars —2— all of which bars are preferably made of angle irons with one of their lengthwise flanges disposed in a horizontal position at the top and preferably 45 projecting outwardly from the upright flanges in the same horizontal plane. These side and end bars are secured at their meeting ends or at the corners by upright corner brackets —3— and suitable fastening bolts 50 —4—, each bracket being preferably formed

of cast metal and provided with upright sides disposed at substantially right angles to each other and fitting against the outer faces of the adjacent ends of the upright sides of the bars —1— and —2—, the upper 60 ends of said corner braces terminating against the under side of horizontal flanges of said side and end bars as clearly shown in Figs. 3 and 4 thereby forming a seat upon which the frame bars rest. These corner 65 brackets are identical in construction and are of greater depth than the vertical depth of the frame bars —1— and —2— and thereby project downwardly some distance below the lower edges of said bars and are formed 70 at their bases with horizontal flanges —5— adapted to rest upon the surface of the ground or other suitable foundation as —6—, the surface of which is substantially flush with the surface of the ground, the 75 entire depth of the frame being sufficiently low to permit wagons to be driven upon the platform by the use of slightly inclined approaches, not necessary to herein illustrate or describe. 80

The opposite sides of each corner brace are provided with inwardly projecting flanges —7— extending under the adjacent ends of the frame bars —1— and —2— and serve the double purpose of reinforcing the corner 85 brackets and forming seats for the support of a superposed diagonal brace —8— which in this instance is separate from the corner bracket but is secured thereto and to the adjacent end of the side and end bars —1— and —2— by clamping bolts —4— as best seen in Fig. 4. These braces —8— extend diagonally across the corners of the frame wholly within the bracket —3— and have 90 their opposite ends abutting against the inner ends of the adjacent ends of the side bars —1— and —2— and provided with pendent flanges having open sided slots —10— through which the clamping bolts —4— are 95 passed, said bolts being also passed through registering apertures in the adjacent end of the bars —1— and —2— and serve to clamp the contiguous portions of the frame bars, corner brackets and braces to each other. 100 These braces serve not only to reinforce or strengthen the corners of the frame including the brackets —3— but also serve as a convenient means for supporting suitable clevises —11— upon which the adjacent ends 105 of the platform levers as —12— may be sus- 110

pended. The central portion of each brace —8— is provided with an aperture —13—, the outer end of which is elongated laterally to receive and form a convenient seat for the 5 supporting pin —14— for the clevises —11—, which latter is made in the form of an open link through which the pin —14— is inserted and then seated in the elongated upper end of the aperture —13— thereby bringing 10 the entire clevis below the upper surface of the frame and practically concealed within the bracket —3—.

The platform supporting beams extend 15 diagonally from each corner toward the center of the opposite lengthwise bar, two of the levers being continuous from side to side of the frame while the other two levers are flexibly connected to the central portions of the continuous levers, the latter being connected 20 to the weighing beam, not shown, but which is located in the usual manner at one side of the frame and connected to the counter levers in the usual way, each lever being provided near its point of connection with 25 its corresponding clevis with a knife bearing —15— for the reception of the platform supports.

In assembling the parts of my invention the corner brackets are placed upon the 30 surface of the ground or other suitable supports the proper distance apart after which the side and end bars —1— and —2— are placed in position with their ends resting upon the upper edges of the corner brackets where- 35 upon the braces —8— are placed in operative position and clamped in place by the bolts —4—, said side bars being additionally clamped to the upper ends of the brackets by bolts —16—. The clevis —11— is then 40 inserted through the aperture —13— and the pin —14— similarly inserted through the link and dropped into its seat in the upper side of the brace —8—, this link being previously attached to the end of the platform 45 supporting lever —12—, the latter device being now ready to receive the platform.

It is apparent that this construction is particularly simple, strong and durable and may be assembled easily and quickly by reason of the fact that it is composed of two parts which enable the entire frame to be manufactured and put into use at a comparatively small cost.

What I claim is:

55 1. In a pitless wagon scales, a rectangular frame comprising side bars and end bars, corner brackets secured to the outer faces of the adjacent ends of the bars and extending some distance below the lower edges of the 60 same, braces diagonally across the inner corners of the frame and engaging the inner faces of said adjacent ends of the bars, flanges on the brackets for supporting said braces,

clevises pivotally mounted upon and depending from the braces, and levers fulcrumed in said clevises and extending inwardly therefrom. 65

2. In a pitless wagon scales, a rectangular frame comprising end bars and side bars, corner brackets secured to the outer faces of the meeting ends of said bars and having inwardly projecting flanges extending under the lower edges of said meeting ends, and braces extending diagonally across and at the inner sides of the corners of the frame 75 and seated on said flanges.

3. In a pitless wagon scales, a rectangular frame composed of side and end bars, upright corner brackets secured to the outer faces of the adjacent ends of said bars and 80 extending some distance below the lower edges thereof, the lower ends of the brackets being provided with laterally projecting flanges, diagonal braces resting on said flanges and engaging the inner faces of the 85 adjacent ends of the bars and holding them against the brackets, and levers operatively connected to said braces.

4. In a pitless wagon scales, a rectangular frame composed of side bars and end bars, 90 corner brackets securing the adjacent ends of the bars and extending some distance below their lower edges to support the frame some distance above the ground, said brackets being provided with inwardly projecting 95 flanges between their lower and upper ends and extending under the lower edges of the frame bars, and braces diagonally across the inner corners of the frame engaging the inner faces of the bars and resting upon said 100 flanges.

5. In a pitless wagon scales, a rectangular frame composed of side bars and end bars, corner brackets securing the adjacent ends of the bars and extending some distance below their lower edges to support the frame some distance above the ground, said brackets being provided with inwardly projecting flanges between their lower and upper ends and extending under the lower edges of the 105 frame bars, braces diagonally across the inner corners of the frame engaging the inner faces of the bars and resting upon said flanges, said braces being provided with vertical openings therethrough enlarged at 110 their upper ends, pivotal pins seated in the enlargements of the openings, clevises supported by the pivotal pins and extending through said apertures, and a system of 115 levers fulcrumed on said clevises. 120

In witness whereof I have hereunto set my hand this 6th day of October 1908.

GERRY JONES.
